(57) CLAIM

The ornamental design for furniture, as shown and described.

DESCRIPTION

FIG. 1 is a perspective view of a first embodiment of furniture showing our new design;

FIG. 2 is a top view thereof;

FIG. 3 is a front view thereof;

FIG. 4 is a right-side view thereof, the left side view being a mirror-image;

FIG. 5 is a perspective view of a second embodiment of furniture showing our new design;

FIG. 6 is a perspective view of a third embodiment of furniture showing our new design; and,

FIG. 7 is a perspective view of a fourth embodiment of furniture showing our new design.

The views not shown of the second, third, and fourth embodiments are the same as the views shown in FIGS. 1, 2 and 4, except for the differences in drawer number and arrangement, and in overall height and width and depth of the furniture.

The broken line showing of handles is for illustrative purposes only and forms no part of the claimed design.
